United States Patent Office

Des. 191,543
Patented Oct. 10, 1961

191,543

SPECTACLE FRAME

Harold Lambert, Shepard St., Plainville, Mass.

Filed May 4, 1961, Ser. No. 65,029

Term of patent 14 years

(Cl. D57—1)

Fig. 1.

Fig. 2.

FIG. 1 is a front elevation of a spectacle frame showing my new design; and

FIG. 2 is a side elevation thereof.

The dominant features of my design reside in the portions shown in full lines.

I claim:

The ornamental design for a spectacle frame, substantially as shown and described.
